COMBINED FERTILIZER AND INSECTICIDE DISPENSER FOR GARDEN USE

Paul C. Bye, 3500 Bucks Bar Road, Placerville, Calif.

Filed Feb. 24, 1964, Ser. No. 78,749

Term of patent 14 years

(Cl. D35—2)

FIG. 1.

FIG. 2.

FIG. 3.

FIG. 4.

FIG. 1 is a side elevational view of a combined fertilizer and insecticide dispenser for garden use, showing my new design;

FIG. 2 is a front elevational view thereof;

FIG. 3 is a rear perspective view thereof; and

FIG. 4 is a front perspective view thereof.

I claim:

The ornamental design for a combined fertilizer and insecticide dispenser for garden use, as shown.
